OXIDATIVE DEMETHYLATION OF LIGNIN
Joseph Marton, Charleston, S.C., and Erich Adler, Göteborg S, Sweden, assignors to West Virginia Pulp and Paper Company, New York, N.Y., a corporation of Delaware

No Drawing. Filed June 6, 1961, Ser. No. 115,100
13 Claims. (Cl. 260—124)

This invention relates to alkali lignin derivatives possessing increased aromatic reactivity and relates particularly to a process for treating lignin recovered from spent alkaline cooking liquors whereby increased aromatic reactivity is imparted thereto.

Lignin, as it occurs in wood, has been extensively investigated in recent years to determine its botanical origin and chemical structure. Lignin has usually been considered to be composed of structural elements such as phenyl and furan groups with an assortment of hydroxyl and methoxyl groups, but, according to modern views on the structure of lignin as it occurs in coniferous woods, this natural product is built up of guaiacyl propane units which are linked together with different types of bonds, in some

5

15

20

2

Typical compounds which incorporate the guaiacyl-propane unit and which are believed to be proper models for building stones of softwood lignins, with probable types of linkages illustrated, are:

instances from one of the carbon atoms of the propyl chain to a position on another aromatic nucleus ortho to a free phenolic hydroxyl group, in other instances linked from one of the propyl carbon atoms to the oxygen of the phenolic hydroxyl on another aromatic nucleus, and sometimes joined simultaneously by both of the foregoing linkages to form a furan-type ring. In still other cases, it is believed that the aromatic nuclei are linked directly.

A typical guaiacyl propane unit may be represented, with the positions on the aromatic ring numbered for reference in the usual manner, thusly:

65

70

It is widely acknowledged, however, that sulfate cooking, in particular, substantially increases the proportion, in softwood lignin, of guaiacyl propane building units having a free phenolic group in the No. 4 position as compared to natural lignin; breakage of aryl-alkyl-ether bonds by thioalcohol groups in alkaline solution is thought to be responsible. Since the structure of lignin, particularly the altered lignin recovered after alkaline digestion of wood, is not known with precision, the reactions which occur cannot be stated with exactness, but it is believed that certain reactions take place, as deduced from studies

of model compounds, which are reasonably consonant with those set forth hereinafter.

As is well known, the presence of a free phenolic hydroxyl increases the aromatic reactivity of both of the adjacent (ortho) positions and of the opposite (para) position on an aromatic nucleus. Since the para position of a guaiacyl propane unit (position No. 1) is usually occupied by the propyl chain and one of the ortho positions (position No. 3) is filled with a methoxyl group, the only remaining position possessing potential aromatic reactivity is the other ortho position, hereinafter termed the No. 5 position, which may or may not be filled by a linkage with a propyl carbon of another guaiacyl propane unit or even by a diphenyl type of bond. Disregarding the relatively small proportions of aldehydic, ketonic, and alcoholic groups on the propane side chains, which are non-aromatic in their reaction conditions, the principal determinative factor in the reactivity of natural lignin is the number of these No. 5 positions on the guaiacylic nuclei which are unoccupied. Similar considerations are valid for hardwood lignin, except that syringyl groups occur in addition to guaiacyl groups.

If the compounds incorporating guaiacyl propane units, as described hereinbefore, represent those which have persisted in softwood lignin through alkaline digestion and recovery processes, it is clear that both free and condensed 5-positions may exist on the aromatic nuclei of the phenolic guaiacyl propane units. Replacement of methoxyl groups (in position No. 3) with hydroxyl groups, moreover, should add two aromatically reactive positions (one ortho and one para, positions 2 and 6) to each aromatic ring having a condensed 5-position, thereby multiplying significantly the total aromatic reactivity of the recovered lignin and enhancing its usefulness in many applications.

For example, in the case of guaiacyl-propane units having a free 5-position, there would be two new reactive positions created ortho and para to the new phenolic OH group, as in the trifunctional demethylation product on the right below, where the reactive positions are marked with an asterisk:

For guaiacyl-propane units containing condensed and thereby blocked 5-positions, the demethylation product becomes bifunctional:

Chemical building units of trifunctional or bifunctional nature, containing guaiacyl propane units converted into pyrocatechol structures, should show considerably increased reactivity towards formaldehyde and greater cross-linking potential in many useful reactions.

Among studies of model compounds of the type believed to occur in lignin have been several studies on the aromatic substituents of guaiacol and guaiacol-based deriva-

tives. For instance, Adler described in *Acta Chemica Scandinavica* 9 (1955), No. 2, 319-334, an analytical method for determination of guaiacyl groups which depended upon sodium metaperiodate liberating methanol quantitatively by a rapid oxidative demethylation process from guaiacol and similar compounds but not from compounds of the veratrol type in which the phenolic group in the No. 4 position had been etherified, forming an additional methoxyl group or a linkage with a carbon of an adjacent compound.

In these determinations the periodate solution was allowed to react at 4° C. upon the model compounds or the protolignins for as long as 90 hours. To obtain substantially complete demethylation, a reaction time of 16 to 48 hours was necessary. The reactions were stopped and the compounds were precipitated by addition of a solution of lead nitrate.

Experiments with "natural lignins," reported in *Svensk Papperstidning*, 61 (1958), 18B, 641-647, showed that these materials also produced methanol upon treatment with sodium metaperiodate, leaving highly polymerized, unreactive lignin residues which were generally insoluble in the usual lignin solvents. In contrast to the rapid production of methanol by guaiacol-type compounds, however, these lignins liberated methanol partially in a rapid phase and partially in a slow phase.

Somewhat similar to the oxidative demethylation process forming a portion of this invention is the reductive demethylation process with hydriodic acid, as given by Moore et al., in the *Canadian Journal of Research*, 15B (1957), page 532, in which high reaction temperatures, a high concentration of HI, an excess of HI, and a lengthy reaction time are required. Reductive demethylation, moreover, is not specific as is oxidative demethylation, for many methoxyl types, including both guaiacyl and veratryl, are attacked, and the reductively demethylated lignin product is polymerized and destructively degraded to a non-useful product.

One of the most widely-available sources of lignin is spent liquor in the sulfate and soda processes which is commonly concentrated and burned to recover heat values and inorganic cooking chemicals. This lignin may be recovered as a water-soluble alkali lignate or as a water-insoluble alkali lignin of low ash content by processing the concentrated, spent cooking liquor according to the principles and methods of U.S. Patent No. 2,464,828. It must be borne in mind, however, that after undergoing the relatively drastic conditions occurring in the digestion of wood by the soda or sulfate processes, the natural lignin in either hardwoods or softwoods is changed to a degree that is unknown and as yet only cursorily investigated.

In studies of alkali lignin recovered from spent sulfate liquor after digestion of coniferous woods, it has been determined that, of the guaiacyl propane units which are believed to comprise the lignin, nearly two-thirds are phenolic in type, having free phenolic OH groups in position No. 4. Of these phenolic guaiacyl propane building units, about one-third possess a position ortho to the phenolic hydroxy (i.e., the No. 5 position on the phenyl ring) which is free and thus accessible to the introduction of methylol groups, for instance, by aromatic reactions. Using very approximate averages, out of every 100 guaiacyl propane building units, therefore, about 22 are phenolic groups and possess free No. 5 positions with resultant capacity to become tri-functional after demethylation, about 42 are phenolic groups and possess blocked No. 5 positions with resultant capacity to become bi-functional after demethylation, and about 36 are non-phenolic groups having etherified No. 4 positions which are apparently incapable of aromatic reactivity or of attaining increased aromatic reactivity by the methods of this invention.

Chemical determination of hydroxyl groups was made according to the method given in *Chemische Berichte*, 88, 617 (1955) in an article by K. Freudenberg and H.

Schluter. The portion of guaiacol groups was determined as reported by Adler in *Svensk Papperstidning* 61 (1958), 18B, 641-647. The quantitative determinations of pyrocatechol structures used the general method outlined on pages 126 and 127 of "Colorimetric Methods of Analysis," vol. 3, by Foster C. Snell and Cornelia T. Snell, D. Von Nostrand & Co., Inc., third edition, 1953, using sodium potassium tartrate and ferrous sulfate as color-developing agents and a properly calibrated spectrophotometer to make direct measurements.

Alkali lignin, recovered according to U.S. Patent No. 2,464,828, has been utilized as an extender of phenol-formaldehyde resins, urea-formaldehyde resins, epoxy resins, isocyanate foams, and styrene-butadiene elastomers. A method of increasing the aromatic reactivity of this lignin has wide usefulness in many practical applications, involving such fields of use as casting sands, paper and fiberglass laminates, wood glues, hardboard, molded articles, insulation foams leather tanning, rubber tires, and rubber heels.

The object of this invention is to increase the reactivity of alkali lignin and more specifically to increase the reactivity of alkali lignin toward aldehydes.

A chemically sound way to attain this objective is to increase the aromatic reactivity of the lignin whereby additional substitution reactions on the guaiacol nucleus may be used for accomplishing such reactions as chloromethylation, the Mannich reaction, phenol-formaldehyde resin condensations, urea-furfural resin condensations, bromination, and nitration, for example. Conversion of guaiacyl structures in softwood-derived alkali lignin into pyrocatechol structures and of syringyl structures in hardwood-derived alkali lignin into pyrogallol structures by replacement of methoxyl groups with hydroxyl groups is a practical way of attaining increased aromatic reactivity.

It has now surprisingly been found that the periodate reaction can be utilized to increase the aromatic reactivity of alkali lignin by carefully controlling the extent of oxidative demethylation and rapidly reducing the product obtained thereby.

Increased aromatic reactivity in alkali lignin is attained according to this invention by dissolving the lignin in a solvent that is inert to the oxidative demethylating agent, adding and rapidly mixing the oxidative demethylating agent, and quickly stopping the reaction with a reductant, the degree of reaction being controlled by removing heat from the reaction materials before mixing or during the reaction and by limiting the duration of the reaction.

It is believed that this invention is effective because the oxidative demethylation reaction of sodium metaperiodate upon alkali lignin does not convert methoxyl groups to hydroxyl groups but instead forms quinone groups which are very reactive and tend to dimerize by diene-addition and form a lignin product of lowered reactivity and insolubility:

Therefore, by adding an excess of a reductant such as sulfur dioxide to remove any excess of the demethylating agent and to convert the demethylated lignin into a somewhat less reactive form, polymerization by diene-addition can be avoided and a stable lignin product of increased aromatic reactivity can be obtained.

The reaction which seems to occur in the oxidative demethylation procedure may be expressed, for a typical guaiacol-propane unit, employing sulfur dioxide as the reductant source, as:

Other oxidants are able to oxidatively demethylate lignin. For instance, the lithium, sodium and potassium salts of bismuthate, persulfate, tungstenate, chlorite, hypochlorite, hypobromite, and hypoiodide anions and chlorine dioxide with chlorine are effective agents. Hydrogen peroxide and ozone are also potentially useful oxidative demethylants. For reduction, a choice might be made among sulfur dioxide and lithium, sodium, and potassium thiosulfate.

The oxidative demethylation reaction may be conducted in any lignin solvent which is itself compatible with periodic acid, for the periodate ion, as liberated by the acid or any of its salts, is actually the active agent in this reaction. The reaction, moreover, is catalyzed by protons, and for this reason alkalis are not usable. Phenol, for example, is usable, but ethanolamine is not. Suitable solvents, for example, are acetic and formic acids and their chlorinated derivatives, 1,4-dioxane, dimethyl sulfoxide, ethylene chlorohydrin, thymol, and the cresols. If an organic solvent is selected, however, it is necessary to add an aqueous acid for the oxidative demethylation step; it is also desirable to have at least two moles of water for each SO2 mole present during the reduction step as a supply source for hydrogen ions.

Experimental work was performed on purified alkali lignin isolated from spent sulfate liquor after digestion of southern pines in a typical kraft papermaking process. The experimental results, as to yield and methoxyl contents of the oxidized and SO2-reduced products, are given in Table 1. The experimental procedure in general which was used is illustrated hereinafter by Example No. 8 in which the reaction was conducted at ice-water temperatures.

EXAMPLES 1-7

In Examples 1, 2, and 3, 1.85 OCH3-milliequivalents of alkali-pine lignin (0.4 g.) were dissolved in 25 ml. of warm 90% acetic acid; after cooling to 20° C., 30 ml. of a 0.14 molar solution of NaIO4 in 60% acetic acid was added. After the time intervals given in Table 1 (10, 30, and 120 min.), gaseous sulphurous dioxide was rapidly introduced, and the mixture was worked up as described in Example 8 hereinafter.

In Example 4, 15 OCH3-milliequivalents of Indulin A (4.4 g.), 250 ml. of 90% AcOH, and 250 ml. of 0.14

molar NaIO_4 solution were used (reaction time 20 min.). After reduction with SO_2 , fractional dilution with water yielded a first precipitate (4a) in 58% yield, and a further one (4b) in 9% yield. Similar yields were obtained in Examples 1-3 for the initial precipitation only. Example 5 was run in a non-solvent acid medium, 0.14 molar H_2SO_4 , at 20° C. for 30 minutes, but the methoxyl content was merely reduced to 13.72%.

Examples 6 and 7 were made with sodium persulfate, $\text{Na}_2\text{S}_2\text{O}_8$, as the sole or principal oxidative agent, but the resulting reduction in methoxyl content was inconsequential. It was concluded that lignin would not be demethylated to an effective degree if reacted upon when in slurry form.

^b Second precipitate.

EXAMPLE 8

Alkali pine lignin, insoluble in water, (4.4 g.) was dissolved in warm acetic acid (90%, 250 ml.), the solution cooled to 2-3° C., and 250 ml. of an ice-cooled solution of sodium metaperiodate (0.14 moles of NaIO_4 dissolved in 400 ml. of water and the solution made up to 1000 ml. with acetic acid) were added. After 3 minutes the reaction was stopped by introducing a vigorous stream of SO_2 gas, while the reaction mixture was cooled with ice-water. After about 3 minutes, when the dark red color of the reaction mixture, indicative of the formation of o-quinones, had turned into a lighter shade, 500 ml. of water were added. The precipitate formed was centrifuged off, washed three times with small amounts of water, and dried in vacuo over P_2O_5 and NaOH . Yield was 3.0 g., i.e., 68% (fraction 8a). While the washing procedure caused part of the material to peptize, another part remained dissolved in the mother liquor which still contained about 35% acetic acid. The wash waters and the mother liquor were combined and diluted with water to 2 liters; the precipitate obtained was collected by centrifuging, washed twice with a small amount of water, and dried as above. Yield was 0.5 g., i.e., 12% (fraction 8b).

As shown by the methoxyl contents of the principal reaction products in Table I, such as (8a), about 50% of the original amount of OCH_3 had been removed. It was thought possible that the residual fraction of the reaction products (30-35% of the alkali lignin used), which were highly soluble in the dilute aqueous acetic acid mother liquors and therefore were not recovered, had considerably lower methoxyl contents, but the methoxyl content of the secondarily-recovered product (8b) was reduced only a 6.84%, i.e., 48% of the original methoxyl as compared to 54% for (8a).

The precipitate in 12% yield (8b), from the second dilution with water, had lost 54% of its original OCH_3 groups. After methylation with diazomethane, this material increased in methoxyl content from 6.84% OCH_3 to 21.52%. Alkali lignin was similarly methylated. After comparison of the results, it was concluded that the majority of the groups formed on oxidative demethylation

and SO_2 -reduction must have been phenolic hydroxyl groups, available for remethylation by diazomethane, and that only a minor amount of the intermediate o-quinoid groups could have undergone dimerization.

The same secondary periodate precipitate in 12% yield (8b) was reduced with sodium borohydride, NaBH_4 . Evaluation of the results by light transmission measurements indicated that small amounts of phenolic α -ketone groups had been formed by the periodate reaction. Possibly 0.05 α -hydroxypropioguacone units or, more probably, 0.02-0.03 vanillin structures had been created per original methoxyl unit.

The solubility of the demethylated products of Examples 1-8 was distinctly lower in the common lignin sol-

vents than that of untreated water-insoluble alkali lignin. This loss in solubility seemed to indicate that some polymerization of the primarily-formed o-quinoid elements had taken place before the reduction with SO_2 was carried out, as discussed hereinbefore.

EXAMPLE 9

This reaction was completely successful in obtaining an unpolymerized product, apparently because of using the molar ratio of 1:1 for $\text{OCH}_3:\text{IO}_4^-$. 8.8 grams of alkali lignin, containing 40 milliequivalents of OCH_3 groups, were dissolved in 500 ml. of 90% acetic acid, cooled to a temperature between 0° C. and 2° C., and mixed rapidly with 285 ml. of 0.14 molar NaIO_4 solution, containing 40 millimoles of iodate equivalent. After exactly 2.0 minutes reaction in which the solution had become violet colored, SO_2 gas was introduced rapidly, turning the solution from violet to brown.

After reduction four liters of water were added to the solution, precipitating the reduced demethylated lignin. The precipitate was centrifuged and washed with water three or four times. For the final washing, a single drop of perchloric acid was added to the wash water to overcome peptization properties of the lignin and promote de-watering of the lignin. The centrifuged, washed lignin was then dried at 60° C. in air.

The yield was 8.1 grams or 92% of the original material. The product was added to dioxane; 5% did not dissolve and was removed by filtering. The dioxane solution was added to ten times its volume of ether, and the precipitate was centrifuged, washed twice with ether, and once with petroleum ether, and dried. The reaction product, after precipitation with water and recovering, was obtained in 92% yield, was completely soluble in dioxane, and contained 8.65% OCH_3 and 0.4% ash or 8.68% OCH_3 on an ash-free basis.

EXAMPLE 10

Repeating the successful molar ratio of Example 9, this experiment used a 1:1 ratio of $\text{IO}_4^-:\text{OCH}_3$. The reaction temperature was raised to 20° C., and the reaction time was increased to 10 minutes. The resulting yield, how-

ever, was only 72%, as given in Table 2, compared to 92% for Example 9, but the methoxyl content was decreased to 6.58%.

In the analytical procedure of phenolic hydroxyl determination, demethylation of alkali lignin did proceed further than in these examples; typically, 65% of the total amount of OCH_3 was recovered as CH_3OH . The discrepancy between the preparative experiments above

ment. It could be stated that 80% of the 2,6-positions of the pyrocatechol nuclei had undergone substitution by CH_2OH groups. Another way of expressing the results is that each newly formed phenolic hydroxyl group permitted almost two new methylol groups to enter the demethylated lignin and that at least 80% of the 2,6-positions of the nuclei of kraft lignin are free, as the following general equation illustrates:

and the typical analytical results is probably due to the fact that, as observed with other lignin preparations, part of the guaiacyl residues are demethylated comparatively slowly and had not reacted during the short time intervals used in these examples as compared to the long time of reaction (2-3 days) applied in the analytical procedure.

EXAMPLES 11-14

Four additional examples are listed in Table 2. In each of these experiments, an amount of alkali lignin containing 5 milliequivalents of OCH_3 groups was used. Potassium persulfate as an alternative oxidative demethylating agent, higher reaction temperatures, and longer reaction times were explored in these experiments. After the oxidation period in each case, the mixture was treated with gaseous SO_2 and then diluted with water. The lignin precipitate was centrifuged, washed with water, and dried.

Table 2

EFFECTIVENESS OF POTASSIUM PERSULFATE AS AN 40
OXIDATIVE METHYLATING AGENT FOR ALKALI LIGNIN

Ex. No.	Demethylating agent (mmols)	Liquid Solvent, percent AcOH	Temp., °C.	Time	Product yield, percent	OCH_3 content, percent
11.	$\text{K}_2\text{S}_2\text{O}_8$ (3.2)	70	50	18 hours	80	11.20
12.	$\text{K}_2\text{S}_2\text{O}_8$ (10)	80	50	18 hours	37	9.70
13.	$\text{K}_2\text{S}_2\text{O}_8$ (5), NaIO_4 (0.5)	60	20	20 min	76	11.83
14.	$\text{K}_2\text{S}_2\text{O}_8$ (5)	80	20	40 min	77	13.58

The demethylated product of Example 9 was condensed with chlorocresol in presence of hydrochloric acid catalyst. The results indicated that 0.28 chlorocresol units per OCH_3 groups originally present in alkali lignin had been introduced into the oxidatively demethylated lignin of this invention, exactly the same as for the original alkali lignin, indicating that the main structural features of the propane side chains responsible for this condensation had not been altered by the oxidative demethylation.

The same demethylated product was then methylolated with formaldehyde and the resultant material was further reacted with chlorocresol, producing a product that had 1.23 chlorocresol units per OCH_3 group present in the original alkali lignin, indicating that 0.95 chlorocresol units per original OCH_3 had reacted with the methylol groups introduced by formaldehyde after demethylation. Calculations showed that the oxidative demethylation procedure had resulted in the introduction of 40 phenolic hydroxyl groups, replacing a corresponding number of methoxyl groups out of each 100 OCH_3 groups of alkali lignin. After methylolation, but not directly, these new phenolic groups enabled 64 chlorocresol units to be linked to the nuclei, meaning that every newly-formed phenolic OH group had enabled 1.6 chlorocresol-reactive methylol groups to be introduced after alkaline formaldehyde treat-

The oxidative demethylation of alkali lignin in acetic acid with sodium metaperiodate is a very rapid reaction. It is most suitably conducted in a continuous process, as in a pipeline reactor, in which the reductant, such as sulfur dioxide, may be added within seconds after iodate addition, according to experimental determinations of optimum reaction time and optimum reaction temperature. Oxidative demethylation is increased by larger amounts of the demethylative oxidant, by a higher reaction temperature, and by a longer reaction time. The use of over two moles of sodium metaperiodate per mole equivalent of methoxyl causes an excessive amount of secondary condensations to occur, giving undesirable amounts of a polymerized, insoluble product and consequent loss of yield.

In a mildly-prepared lignin, such as Bjorkman lignin which is now considered to be very close to natural lignin in a structural sense, every third guaiacyl propane "building unit" has a free phenolic OH group. The lignin of either coniferous or deciduous woods when subjected to alkali cooking undergoes certain different structural changes; from the viewpoint of this invention the most important consists of that part of the ether-phenolic linkages which are broken by cooking, producing alkali lignin which has free phenolic groups in about two-thirds of the building units. Because the method of this invention works only with such building units having free phenolic hydroxyls, the economic advantages are obvious for alkali lignin as compared to natural lignin.

After oxidative demethylation of alkali lignin according to the methods of this invention, the propyl side chains are unchanged, as demonstrated by the chlorocresol experiment described hereinbefore and by other evidence; furthermore, carbon-to-carbon bondings, between propyl carbon atoms of two adjacent side chains, between a propyl carbon and a carbon of a guaiacyl nucleus, or between the carbons of two guaiacyl nuclei, are not

broken to a measurable extent. Even more significantly, for the 22% of the guaiacyl propane units having ether bonds at the No. 4 position, the ether bonds in which an oxygen atom links the carbon of a guaiacyl nucleus to the carbon of a propyl side chain or to the carbon of another guaiacyl nucleus, are also not broken. In the oxidative demethylation reaction of this invention, only a certain type of ether linkage, termed a methoxyl group, in which oxygen joins the carbon of a guaiacyl nucleus to the carbon of a free methyl group, is attacked, provided that a phenolic hydroxyl group is in ortho position to the methoxyl group. The reaction of this invention, therefore, is specific.

Moreover, as demonstrated experimentally with Example No. 9 hereinbefore, the reaction is easily controllable and technically uncomplicated. A continuous process which includes the continuous regeneration of the iodate ion to the periodate ion by electrolytic oxidation is economically sound and can produce the reactive lignin product of this invention at a cost rendering it attractive as a useful substituent in phenolic resins in the same manner as, and even more usefully than, the original alkali lignin.

When the product of this invention is treated with formaldehyde, a large number of reactive benzyl alcohol groups, i.e., methylol groups, are introduced into the guaiacyl nuclei than can be introduced into the guaiacyl nuclei of original or ordinary alkali lignin. These methylol groups, by their inherent nature, as demonstrated hereinbefore with chlorocresol, can be condensed with phenols, cresols, etc., and provide substitution sites for extending and reacting with phenolic materials to form thermosetting resins as is well known in the art.

Practical examples of lignin uses, and particularly of uses for a lignin of increased chemical reactivity, are, in the resin field: phenol-formaldehyde-lignins for molded products, as taught in No. 2,357,090 and No. 2,282,518; lignin-containing coating compositions, as taught in No. 1,899,526 and No. 2,242,601; phenol-formaldehyde-lignin shell-molding resins, as taught in No. 2,751,650; phenol-formaldehyde-lignin resin adhesives for lignocellulose products such as plywood, as taught in No. 2,878,197; and phenol-formaldehyde-lignin resoles for impregnating paper in the manufacture of laminates, as taught in No. 2,683,706 and No. 2,725,321. Other uses may be illustrated with the elastomer field by No. 2,608,537 for lignin-rubber elastomers, No. 2,906,718 for lignin-rubber-polyisocyanate rubber, and No. 2,854,422 for lignin-diisocyanate elastomers.

We claim:

1. The method of oxidatively demethylating alkali lignin which comprises reacting said lignin with an oxidizing agent, selected from the group consisting of sodium and potassium salts of bismuthate, periodate, persulfate, tungstenate, chlorite, hypochloride, hypobromide, and hypiodide anions, chlorine dioxide with chlorine, hydrogen peroxide, and ozone, to convert guaiacol structures into o-quinoid structures, and, before the occurrence of a significant degree of polymerization by diene addition of said quinoid structures, stopping the reaction with a reducing agent selected from the group consisting of sulfur dioxide, sulfuric acid, sodium thiosulfate, and potassium thiosulfate, to convert said o-quinoid structures into pyrocatechol structures.

2. The method of claim 1 wherein the lignin is dissolved in a solvent which contains protons and is inert to the oxidizing agent.

3. The method of claim 1 wherein the reduction is conducted in a solvent which is a source of hydrogen.

4. The method of claim 1 wherein both oxidative demethylation and reduction are conducted in aqueous acetic acid.

5. The method of claim 1 wherein the oxidative demethylating reaction is carried out at temperatures lower than ambient.

6. The method of claim 4 wherein the reaction occurs for a time inversely proportioned to the temperature, a temperature of 0-4° C. corresponding to 2.0 minutes.

7. The method of increasing the aromatic reactivity of alkali lignin comprising the reacting of said lignin with up to 1.5 moles of sodium metaperiodate per mole of methoxyl groups in the lignin and subsequently adding sulfur dioxide, said lignin being dissolved in a solvent inert to sodium metaperiodate, containing protons, and capable of supplying hydrogen.

8. The method of claim 7 wherein the reaction is conducted at temperatures of 0-4° C.

9. The method of claim 7 wherein the reaction proceeds for up to 2.0 minutes.

10. The method of increasing the aromatic reactivity of alkali lignin by reacting said lignin, dissolved in warm 90% acetic acid at a lignin concentration of 1 to 5% and cooled to 0 to 20° C., with sodium metaperiodate at 0 to 20° C. for 1 to 3 minutes, employing up to 1.0 moles of said periodate per 1.0 moles of methoxyl groups in the lignin, and reducing the reaction product with sulfur dioxide while cooling.

11. The method of preparing water-insoluble and substantially ether-insoluble derivatives of alkali lignin having increased aromatic reactivity, as characterized by capacity to add larger proportions of methylol groups by reaction with formaldehyde as compared to the original alkali lignin, comprising oxidatively demethylating said lignin to convert guaiacol structures into o-quinoid structures and, before the occurrence of a significant degree of polymerization by diene addition of said quinoid structures, reducing said o-quinoid structures to pyrocatechol structures.

12. The method of claim 11 wherein the alkali lignin is oxidatively demethylated with an agent selected from the group consisting of the sodium and potassium salts of bismuthate, periodate, and tungstenate and wherein the o-quinoid structures are reduced to pyrocatechol structures with an agent selected from the group consisting of sulfur dioxide, sulfuric acid, sodium thiosulfate, and potassium thiosulfate.

13. The product produced by the method of claim 11.
